DESIGN FOR A COMBINED LAMP AND AIR CIRCULATOR

Alexander E. Blumenthal, Pittsburgh, Pa.

Application April 14, 1938, Serial No. 76,494

Term of patent 3½ years

To all whom it may concern:

Be it known that I, Alexander E. Blumenthal, a citizen of the United States and a resident of Pittsburgh, Allegheny County, Pennsylvania, whose post office address is 1805 Boulevard of Allies, Pittsburgh, Pennsylvania, have invented a new, original, and ornamental Design for a Combined Lamp and Air Circulator, of which the following is a specification, reference being had to the accompanying drawing, forming a part thereof.

Fig. 1 is a side elevational view of a combined lamp and air circulator showing my new design with the essential parts in solid lines.

Fig. 2 is a top plan thereof.

I claim:

The ornamental design for a combined lamp and air circulator, substantially as shown and described.

ALEXANDER E. BLUMENTHAL.
